CLAIM

We claim the ornamental design for a lanyard, as shown and described.

DESCRIPTION

FIG. 1 is a perspective view of our lanyard.

FIG. 2 is a side elevation view thereof.

FIG. 3 is a side elevation view thereof.

FIG. 4 is a front elevation view thereof.

FIG. 5 is a rear elevation view thereof.

FIG. 6 is a top plan view thereof; and,

FIG. 7 is a bottom plan view thereof.

The broken lines in the drawings illustrate features of the article to which the design is applied that forms no part of the claim.
